CLAIM

We claim the ornamental design for the chair, as shown and described.

DESCRIPTION

FIG. 1 is a front perspective view of a chair embodying the present invention;

FIG. 2 is a rear perspective view of the chair;

FIG. 3 is a front view of the chair;

FIG. 4 is a side view of the chair;

FIG. 5 is a rear view of the chair; and,

FIG. 6 is a top view of the chair.

The broken lines shown in the drawings are for illustrative purposes only and form no part of the claimed design.
